US0D1085204S

(12) **United States Design Patent** (10) **Patent No.:** **US D1,085,204 S**
(45) **Date of Patent:** **** Jul. 22, 2025**

(54) **CAMERA MOUNT ADAPTER**

(71) Applicant: **GoPro, Inc.**, San Mateo, CA (US)

(72) Inventors: **John George Muhlenkamp, IV**,
Mapleton, UT (US); **Nicholas D. Woodman**, Big Sky, MT (US); **Huy Phuong Nguyen**, Alpine, UT (US)

(73) Assignee: **GoPro, Inc.**, San Mateo, CA (US)

(**) Term: **15 Years**

(21) Appl. No.: **29/899,596**

(22) Filed: **Aug. 10, 2023**

(51) LOC (15) Cl. **16-05**

(52) U.S. Cl.

USPC **D16/242**

(58) **Field of Classification Search**

USPC D14/229; D16/206, 237, 240, 242, 243,
D16/244

CPC G03B 17/566; G03B 17/561; F16B 1/00

(57) **CLAIM**

The ornamental design for a camera mount adapter as shown and described.

DESCRIPTION

FIG. 1 is a front, upper, right perspective view of a camera mount adapter of our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

Broken lines of equal length (e.g., dash-dash) represent unclaimed subject matter and form no part of the claimed design.

1 Claim, 7 Drawing Sheets
